UNITED STATES PATENT OFFICE.

EDWARD J. ELSAS, OF KANSAS CITY, MISSOURI.

HINGED FOLDING SQUARE.

Application filed October 14, 1924. Serial No. 743,602.

This invention relates to mechanics' squares and more particularly to standard framing squares.

The object of the invention is to provide a simple and efficient square of this character so constructed that the two arms thereof may be folded together in overlapping relation for convenience in packing and carrying.

Another object is to provide a square of this character equipped with means for positively holding the members thereof at the correct angle when open and which when subjected to a sudden jolt or to undue stress will automatically collapse without any of its uniting parts or its members being strained.

Another object is to provide a square of this character equipped with means for automatically retaining it taut and which may be easily tightened in case of wear.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed without departing from the spirit of the invention.

In the accompanying drawings:—

Fig. 1 represents a plan view of a square constructed in accordance with this invention showing one face of the square;

Fig. 2 is a similar view taken from the other face with the arms broken off for convenience in illustration;

Fig. 3 is a detail perspective view of the hinged end of one member of the square;

Fig. 4 is a similar view of the cooperating face of the hinged end of the other member;

Fig. 5 is a transverse section taken on the line 5—5 of Fig. 1.

Fig. 6 is a similar view showing the members in folded position.

Fig. 7 is a transverse section showing the members in folded position; and

Fig. 8 is an edge view of the long arm of the square taken from the inside; and

Fig. 9 is a similar view of the short arm.

In the embodiment illustrated, the square 1 is constructed of two hingably connected members or blades 2 and 3 which in general are similar to those of an ordinary square, 55 being thicker at their inner or connected

ends and gradually tapering toward their outer ends. The two members or blades are made thicker at their outer edges and tapered toward their inner edges as shown in Figs. 3 and 4 and they are hinged together so that they may close with onelapping over the other as shown in Fig. 6, the shorter or smaller blade 3lapping over the larger. The longer or larger blade 2 is provided on one face thereof with a cut out portion 4 of a width corresponding to the width of the smaller blade 3 with a shoulder 5 formed at the inner edge of the said seat 4 so that when blade 3 is folded over blade 2 the thin inner edge thereof will abut the shoulder 5 and the blade 3 will be substantially flush with the portion of blade 2 beyond the shoulder. The seat 4 is made deeper at its inner end gradually merging at its outer end flush with the body portion of the blade 2.

The hinged ends of the blades 2 and 3 with their opposed cooperating faces are shown in Figs. 3 and 4 and when overlapped and connected appear as shown in Fig. 6 being united by a heavy short screw 6 having its head countersunk in one or the other of the members. The body of this screw is threaded through the other member, the thread being of such a tight fit that the hinge action of the blades cannot loosen it. The adjacent hinged faces of the two members of the square are each provided with a shallow space shown at 7 and 8 respectively arranged over the central area of said faces to provide for clearance and to permit the hinged portion of the two members to be sprung slightly together by the tightening of the screw which by having a tight thread through one member and a counter-sunk head in the other provides for the drawing tight of the two members at their hinged connection insuring the tight retention of the parts and preventing them from easily acquiring play or lost motion.

A non-corrosive thin, frictionless washer 9 is placed between the hinged faces of the two members around the screw 6 to insure easy action at the hinge and prevent sticking of the members from the effects of corrosion or rust.

Adjacent the circular seat 8 of the blade 3 near the inner edge thereof is a concentric rib 10 which tapers in thickness from its outer edge inward and is designed to operate in a similarly shaped seat 11 formed in

the opposed face of the blade 2 adjacent the seat 7 thereof said rib 10 and seat 11 being concentric with the screw 6.

Blade 3 is provided adjacent its seat 8 with a tongue 12 extending in a plane substantially at right angles to the rib 10 and which is designed to abut when the members are opened against a shoulder 13 formed at the end of blade 2 as is shown clearly in Fig. 2. Blade 2 has a shoulder 14 adjacent its seat 7 near its outer edge against which the edge of the seat carrying portion of the blade 3 abuts when the members are in open position as shown in Fig. 2. The main member or blade 2 is equipped with a flat longitudinally extending spring 15 at its inner edge adjacent its hinged end. This spring 15 is shown formed by slitting the blade 2 longitudinally and providing on the free end thereof a laterally extending lug 16 slightly beveled on its outer face 17 and against which the beveled end of a rib 19 on the inner edge of the blade 3 abuts when in open position thus holding the blades in open relation at right angles to each other. The lug 16 is spaced inwardly a slight distance from the free end of spring 15 and said end is reduced in thickness and overlies the beveled or inclined track or rib 19 formed on blade 3 concentric with the screw 6. This inclined track 19 is made thicker at its outer edge gradually merging at its inner end into the body of blade 3. This engagement of spring 15 with the inclined track 19 holds the members of the square tightly in open position and compensates for any possible wear on the meeting faces of the blades at their hinged connection. The track 19 is equipped with a plurality of radiating notches 20 which are designed to receive a knife edge 16^a carried by lug 16 so that the blades 2 and 3 may be held at any desired angle. The notches 20 being marked according to the angle at which the blades will be held when the lug is engaged with them.

The short blade 3 is equipped with a transverse groove or notch 21 which is designed to receive the knife edge 16^a of lug 16 when the square is closed thus holding the blades against accidental separation.

The spring 15 is made broad, thin and long and is adapted to slightly buckle and permit the beveled lug 16 to pass over track 19 when any sudden inward jolt occurs upon the outer end of either blade so that the blades will collapse and thus avoid injury to the square.

The blades are formed with suitable gradations disposed along the edges thereof.

The notches 20 are also formed with gradations so that readings may be made with the square.

In the use of this square the parts being in folded position as shown in Fig. 6 when it is desired to use the square all that is necessary is to swing the shorter blade 3 outward into right angular position relative to the blade 2 and when it reaches this position the lug 16 will snap behind the beveled end of track 19 and the tongue 12 will abut the end of blade 2 and thus hold the square true and right angled when fully opened.

To close the square the spring 15 is moved outwardly to release the lug 16 from the end of track 19 and permit the lug to slide over track 19 and the blade 3 to be moved inwardly into lapping relation with the blade 2 the lug on the spring snapping into the cross notch on blade 3 and locking the blades in collapsed position.

I claim:

In a measuring instrument, pivotally connected sections, each section having a cut out portion, the cut out portions of the sections contacting to provide a hinge joint, one of said sections being formed with a slit extended longitudinally of the edge of the section, and defining a spring finger, a lug extending from one end of the spring finger, a rib on the other of said sections and having notches formed therein adapted to accommodate the lug to hold the sections of the measuring instrument in adjusted positions, and a screw extending through the sections to connect the sections.

In testimony that I claim the foregoing as my own, I have hereto affixed my signature.

EDWARD J. ELSAS.
